1 Claim. (Cl. 100—282)

The present invention relates to an improvement in a machine press.

A particular object of the invention is to provide a machine press that can apply a large force effectively, although very simply constructed. A further object of the invention is to provide a press in which the pressing power of the ram increases in comparison with the revolving power of the crank, whereby it is possible to obtain a large pressing power with a small motive power and to provide a compact but highly efficient press.

Machine presses which have hitherto been used in general are designed in such a way that a vertical ram is connected with a crank shaft to which motive power is conveyed from a flywheel, and thereby converting the rotation of the crank to a vertical movement and conveying the movement direct to the vertical ram.

On account of such a structure as described above, the pressing power of the vertical ram is almost same as the resolving power of the crank and accordingly, in order to increase the pressing power, it becomes necessary to increase the motive power supplied to the crank.

In case of the so-called power press which needs large motive power, the size of the press as a whole must therefore become large. Thus, it has disadvantages such as being not only uneconomical in every respect but also difficult to operate and yet high in price.

To overcome such disadvantages of the conventional press as above-mentioned, the inventor has designed a compact but highly efficient press which produces a large pressing power with a small motive power by means of, as explained in the following, setting a lever-plate connected to a crank mechanism so that it swings with the main shaft as a fulcrum, the lever-plate and a ram-linking plate being pivoted on the same main shaft, and the two plates being coupled to each other by a linking mechanism when the ram comes down, thus increasing the pressing power of the ram in comparison with the revolving power of the crank.

The invention will now be described in connection with the accompanying drawings in which:

FIG. 1 is a front view of an embodiment of the present invention; FIG. 2 is a vertical sectional view of the embodiment of FIG. 1; FIG. 3 is a horizontal section along the line A—A in FIG. 2; FIG. 4 is a side view of the second embodiment of the present invention partially in section; FIG. 5 is a horizontal section thereof; and FIG. 6 is a side view of a third embodiment partially in section.

In the drawings, the upper end of a lever 1 is pivoted on a main shaft 3 which is positioned at the upper front in the frame 2 of the press, and the lower end of lever 1 has a long slit 6 therein in which a sliding piece 5 of a crank shaft 4 slips.

By a crank mechanism, the lever 1 swings with the said main shaft 3 as a fulcrum. On the main shaft 3 is pivoted the back center of a two part ram-linking plate 7 in such a way as to hold the lever 1 on both sides thereof, the parts of the ram-linking plate being joined by a connecting part 7'. The top of the ram-linking plate 7 is also pivoted on a pin 8 on an adjusting screw cylinder 10' which is threaded onto an adjusting screw shaft 10 of the ram 9. Further, the upper end of the ram-linking plate 7 is always pulled backward by a spring 11, whereby it tends to push the ram 9 upward.

2

The lever 1 and the ram-linking plate 7 are linked with each other by a pawl means 12. This mechanism consists of a pawl 13 pivotally mounted on a pin 14 on the upper part of the ram-linking plate 7, the pawl 13 being positioned so that the free end thereof can fall into a notch 15 on the upper side of the lever 1 when a detent 17 pivotally mounted on frame 2 is swung out from in front of projection 13' on the pawl 13 by pressing down on a pedal 16 linked by link 18 to the other end of detent 17, thus releasing the pawl 13. The weight of pawl 13 causes its free end to fall into the notch 15.

Character 19 indicates a motor; 20 is a belt pulley; 21 is a pinion gear; 22 is a gearwheel to turn the crank 4 around; and 23 is a flywheel (FIG. 1).

The press works as follows. When the motor 19 runs and the belt pulley 20 rotates, the gearwheel 22 engaged with a group of pinion gears 21 turns and so does the crank 4. Thereby, the sliding piece 5 slides inside the long slit 6 in the lever 1, and makes the lever 1 swing up and down with the main shaft 3 as a fulcrum.

When the pedal 16 is not stepped on, the movement of the lever 1 is not conveyed to the ram-linking plate 7, because the hook 17 catches on a projecting part 13' of the pawl 13, preventing the latter from dropping into the notch 15 of the lever 1. On the other hand, when the pedal 16 is stepped on and goes down with an axis 16' at the other end as a fulcrum, the link 18 is pulled down, releasing the hook 17 from its contact with the projecting part 13' of the pawl 13. Then, the pawl 13, under the effect of gravity drops into notch 15 of the lever 1.

Accordingly, when the lever 7 revolves with the main shaft 3 as its center, and its end pushes the ram 9 downward through the adjusting screw cylinder 10' and the adjusting screw lever 10. On this occasion, the ram 9 is, as stated above, given a pressing power by the lever 1 through the ram-linking plate 7 which is far shorter than the lever-plate 1 and consequently, the pressing power increases remarkably.

When the lever 1 moves downward the next time in accordance with the rotation of the crank 4, the projecting part 1' of the lever 1 presses the connecting part 7' of the ram-linking plate 7. Thereby, the ram-linking plate is turned in the opposite direction (clockwise) with the main shaft 3 as a fulcrum, pulling the vertical ram 9 up.

FIGS. 4 and 5 illustrate the second embodiment of the present invention. In this case, the motor 19, the belt pulley 20 and the flywheel (not shown) are set inside the frame 2 of the press. All the reference numerals in these drawings designate the same parts as in FIGS. 1 and 2. Further, it should be noticed in the second embodiment that the lever 1 has a long slit 1" in which the shaft of the gear 22 slides, and that making use of a space inside the frame 2 of the press, the swinging end of the lever 1 extends to the bottom, where it is connected with the crank mechanism 4. Thus, the pressing power of the ram 9 is increased further as the result of the lever 1 being very long.

FIG. 6 illustrates the third embodiment of the present invention. In this case, the motor 19 and the belt pulley 20 are set inside the frame 2 of the press, having the crank mechanism 4 located between them.

As already explained, the present invention consists of pivoting on the same main shaft both the lever which by the crank mechanism swings with the main shaft as a fulcrum and the ram-linking plate which is connected at its other end with the ram, and linking the lever with the ram-linking plate by a pawl mechanism when the ram comes down.

Because of this structure, the present invention has advantages that the pressing power of the ram increases in comparison with the revolving power of the crank, whereby it is possible to obtain a large pressing power

with a small motive power and to manufacture a compact but highly efficient press.

What I claim is:

A machine press comprising a vertically movable ram member, a ram linking plate pivotally coupled to said vertically movable ram member, a main shaft mounted in a fixed position on said press and on which said ram linking plate is pivotally mounted and from which said ram plate extends in one direction toward said pivotal coupling, a lever having one end pivotally mounted on said main shaft and extending from said main shaft in substantially the opposite direction from the direction the ram linking plate extends from said main shaft, drive means coupled to the other end of said lever for pivoting said lever around said main shaft, said drive means including a gear wheel having its center positioned between the ends of said lever, said gearwheel having a shaft

about which said gearwheel rotates, said lever having a slot therein, a crank on said gearwheel shaft and sliding in said slot, said slot extending in the direction of the length of said lever and pawl means coupling said ram linking plate and said lever and engaging said lever at a point substantially on the opposite side of said main shaft from the coupling of said ram linking plate and said ram.
